(57) **CLAIM**

The ornamental design for a kisser button for archery, as shown and described.

DESCRIPTION

FIG. 1 is an isometric view of a kisser button showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an isometric view of the kisser button showing my new design connected to a bowstring.

The broken lines shown on the drawings represent unclaimed portions of the design and form no part thereof.
